ACTIVATION OF PEROXIDE WASHING AND BLEACHING BATHS

BACKGROUND OF THE INVENTION

The present invention relates to a process for the activation of peroxide compounds in aqueous solutions used for washing and bleaching, or for disinfection and decontamination, and also to solid compositions containing both a peroxide compound and the activator.

In washing and bleaching products it is known to use peroxide compounds such as hydrogen peroxide, sodium peroxide, sodium perborate, sodium percarbonate, urea peroxide, etc. These peroxide compounds provide a satisfactory bleaching action when the washing liquid is used at or close to boiling temperature, but their action is relatively slow at lower temperatures and for treatments of short duration. This disadvantage is important because of the increasing use of washing machines the operating temperature of which is for example from 30° to 60°C. and the washing time from 10 to 15 minutes.

It is for this reason that it has been proposed to add activators which even at low temperature permit washing and bleaching by means of liquids containing peroxide compounds while providing under these conditions good bleaching action and also satisfactory removal of stains. As examples of known activators, mention may be made of the anhydrides of lower carboxylic acids, for example, acetic anhydride, substances containing one or more nitrogen atoms and at least two acyl groups bonded to the same nitrogen atom, particularly tetraacetyl ethylenediamine, and also acylated derivatives of 2,4,6-trihydroxy-1,3,5-triazine, preferably trisacetyl cyanurate. Among these compounds the acetylated derivatives are the most effective, but their penetrating odor considerably limits their utility.

SUMMARY OF THE INVENTION

It has now been found that the acylation products of dioximes, particularly the reaction products of glyoximes and an acylation agent constitute remarkable activators for washing and bleaching baths containing peroxide compounds.

According to the invention, a peroxide compound in an aqueous medium is activated by the reaction product of a dioxime and an acetylation agent.

Also according to the invention, a solid composition useful for producing washing and bleaching baths is comprised of a solid peroxide compound and the reaction product of a dioxime with an acylation agent, which is effective as an activator for the peroxide compound.

BRIEF DESCRIPTION OF THE DRAWINGS

Each of the figures is a diagram wherein the time of soaking in hours (abscissa) has been plotted against the soil eliminated in percent (ordinate).

In FIG. 1, curves I and II concern soaking with a peroxide compound without an activator, curves III and IV concern soaking with a peroxide compound in the presence of 0.1 g. of an acylated dioxime, curves V and VI concern soaking in the presence of a peroxide compound and 0.5 g. of an acylated dioxime and curves VII and VIII concern soaking in the presence of a peroxide compound and 1.0 g. of an acylated dioxime. The soil

to be eliminated is tea (curves I, III, V and VII) and wine (curves II, IV and VI).

In each of FIGS. 2, 3, 4 and 5, curve I concerns soaking with a peroxide compound without activation and curves II, III and IV concern soaking with a peroxide compound in the presence of diacetylated dimethylglyoxime, diacetylated glyoxime and diacetylated methylglyoxime, respectively.

In FIGS. 2 and 4, the diagrams concern tests of fabrics soiled with tea and in FIGS. 3 and 5, the diagrams concern tests of fabrics soiled with red wine.

DESCRIPTION OF THE INVENTION

Up to the present time, it has not been possible to determine the structure of the acylation products of dioximes which, according to the invention have been found to be highly effective as activators for peroxides, so that it is not known whether these compounds are di-N-acylated dioximes or di-O-acylated dioximes.

Among the acylation products of dioximes according to the invention the preferred compounds are acylation products, the acyl group of which contains from two to four carbon atoms, particularly acetylation products. The compounds which can be used according to the invention are preferably the diacylated products of glyoxime and dialkylglyoximes in which the alkyl group contains from one to 12, preferably from one to four carbon atoms.

A particularly suitable compound is diacetylated dimethylglyoxime, the formula of which is probably one of the following:

This compound is easily obtained by reacting acetic anhydride with dimethylglyoxime by the usual acetylation techniques. Its composition has been determined by elementary analysis and mass spectrometry. It is obtained in the form of a white powder of crystalline appearance and surprisingly is practically odorless, so that it has an undeniable advantage in the present application. The use of the activators according to the invention makes it possible to obtain a sufficient degree of whiteness even at relatively low temperatures, so that in the process according to the invention the objects to be treated may be brought into contact with an aqueous solution containing the peroxide compound and the activator at temperatures between ambient temperature and 80°C.

The process according to the invention is effective for bleaching paper pulp, textile materials, greases, oils, and all materials as well as all compounds usually bleached by means of peroxide solutions. These aqueous solutions of peroxide compounds and activators may also be used for decontamination and disinfection.

The amount of peroxide compound varies with the nature of the objects to be treated and the degree of whiteness which is desired; thus, for the decoloration of

oils and greases it may be necessary to use larger amounts of peroxide compounds than for the bleaching of textile materials.

The diacylated dioximes used as activators in the present invention are effective even when they are present in the washing and bleaching baths at the rate of 0.05 mole per gram-atom of active oxygen; it is obvious that larger amounts may be used, but it scarcely appears advantageous to use more than one mole of activator per gram-atom of active oxygen.

For the purpose of carrying out the process according to the invention, the activators proposed may be added to the washing and bleaching baths at the time of use.

When the activators proposed are in solid form, which is most frequently the case, they may also be mixed, preferably provided with a protective coating which is soluble in water or capable of dispersion therein, such as certain polyethylene glycols, polyvinyl alcohol, or other similar materials — with the washing or bleaching powders containing peroxide compounds, so as to have available a pulverulent mixture ready for the preparation of the washing or bleaching bath by dissolving in water.

Such ready-to-use mixtures may contain, in addition to the peroxide compound and the activator, anionic or non-ionic detergents having a washing action, alkaline substances regulating pH, and assisting the washing action, for example, carbonates, phosphates, pyrophosphates, tripolyphosphates, and silicates, antiredposition agents such as carboxymethyl cellulose, optical bleaching products, proteolytic and/or amylolytic enzymes, stabilizers, anti-corrosive agents, etc.

The following examples further illustrate the best mode currently contemplated for carrying out the invention, except of course those examples wherein no activator has been used or wherein an activator known in the art has been used for the purposes of comparison. The examples which illustrate the invention must not be construed as limiting the invention in any manner.

EXAMPLE 1

In this example, the activities imparted by diacetylated dimethylglyoxime (DMGA) and by a known activator, triacetylcyanurate (TACA), to a perborate washing powder containing no activator and used for washing clothes under mild temperature conditions are compared.

The washing tests were carried out in a "General Electric WA 550B" washing machine which treats the cloths in the following manner:

filling, maximum duration 5 minutes;
washing with 75 liters of preheated water, time: 14 minutes;
draining of water, time: about 1 minute;
rinsing for a period of 15 minutes with cold water;
spin drying for 5 minutes.

The total duration of a washing cycle is therefore about 40 minutes.

The water feeding the machine has a hardness of 16 to 17 French hydrotimetric degrees; its temperature in the machine is 40°C. ± 1°C.

The washing powder used at the rate of 2 g. per liter of 150 g. per cycle is a commercial product. Its composition, determined by analysis is as follows, in percent by weight:

surface active organic materials	20
sodium silicate	5
sodium tripolyphosphate	30
sodium pyrophosphate	5
sodium sulphate	10
tetrahydrated sodium perborate	20
water of crystallization, cellulose derivatives, optical bleaching agent, etc.	10
	100

10 The material to be washed is composed of two parts: a white load and various test pieces intended to evaluate washing effectiveness.

The load, with a total weight of 3.5 kg., is composed of various pieces of about 75 cm. in length and 50 cm. in width. These pieces are of mixed cloth based on cotton (65 percent) and polyester (35 percent). The whiteness of the cloth, measured by its reflectance in blue light, is 88.0 ± 0.1 percent referred to magnesium oxide.

15 Various test pieces of about 100 square cm. (12.5 cm. × 8 cm.) are sewn on the load. Fifteen types of test pieces were used at the rate of 10 test pieces per type. The fabrics to be tested were distributed in the following four groups;

20 First group: test pieces intended to measure the detergent effectiveness of the washing product.

Second group: fabrics covered with soil sensitive to the action of the enzymes used in washing powders.

25 Third group: test pieces soiled by products capable of decoloration by oxidation.

Fourth group: white fabrics serving to evaluate the amount of soil redeposition during washing.

30 The first group comprises three different cottons covered with pigmentary soil based on lampblack. These fabrics were prepared by the following specialized organizations: EMPA (Switzerland), TEST FABRICS (U.S.A.), and WFK KREFELD (West Germany).

35 The second group comprises EMPA 112 and 116 soiled cottons. One of the cottons is impregnated with soil containing blood, milk, India ink, etc.; the other is soiled with cocoa.

40 The third group is composed of mixed cloth soiled with seven different stains; the staining was obtained by impregnating the fabric with a concentrated solution of the staining element, padding the impregnated cloth and drying in the open air, this staining cycle being repeated three times in succession. Four stains were made with natural fruit juices — blackcurrant, bilberry, cherry, and grape and the other three are based on tea, coffee and red wine.

45 In the fourth group, three types of white fabrics were used to evaluate the antiredeposition power of the washing product; two test pieces are cotton and a third is a mixed cotton-polyester fabric.

50 The effect of the washing treatment on the various test pieces is measured by the variation of their whiteness. The latter is always determined on the hidden face of the test piece, that is to say the face in permanent contact with the load. Whiteness is measured with the aid of an ELREPHO reflectometer (Zeiss) giving diffused lighting of the test piece and having an effective wavelength of 457 nanometers; the values obtained for reflectances are given in percent, referred to magnesium oxide.

55 For each soiled test piece the rate of soil elimination in percent, that is to say the ratio,

Table 1a

Activator	No. of washing cycles	Relative efficiency (unactivated powder = 100, result after 3 cycles)			
		Detergent action	Enzyme action	Bleaching action	Antiredep- osition action
TACA 0.4 g./l.	3	88	109	205	100
DMGA 0.35 g./l.	1	—	107	167	89
	2	—	120	203	117
	3	93	126	229	118

(soil eliminated/soil to be eliminated) $\times 100$, is given by the formula:

$$\frac{\text{reflectance after washing} - \text{reflectance before washing}}{\text{initial reflectance (before formation of stains)} - \text{reflectance before washing}} \times 100.$$

The mean rate of soil elimination is equal to the arithmetic mean of the above results for all the test pieces of the same group.

In the case of unsoled fabrics, the soil to be eliminated obviously corresponds to initial reflectance, and soil eliminated or gain in whiteness corresponds to the difference between reflectance after washing and initial reflectance.

The relative efficiency of the various washing powders is expressed by the ratio, multiplied by 100, between the mean rates of elimination of soil with the aid of an activated powder and of an unactivated powder.

The tests carried out made it possible to compare the following products:

perborate powder without activation,
perborate powder activated by trisacetylcyanurate (TACA),
perborate powder activated by discetylated dimethylglyoxime (DMGA).

Detailed results of the tests relating to the fourth group of test pieces, that is to say, measurement of bleaching power, are given in Table 1 below.

It is therefore seen that, in relation to the results obtained after three washing cycles with the aid of an unactivated perborate powder, the powder activated with DMGA has a bleaching power twice as great after only two washing cycles. For an equal number of cycles the powder containing DMGA has a detergent power almost identical to that of the powder without activator (the differences measured are not visible to the eye); the enzymatic and antiredeposition powers are improved respectively by 26 and 18 percent.

EXAMPLE 2

In this example, the influence of the diacetylated dimethylglyoxime (DMGA) content on the activation of a perborate washing powder is determined. In addition, comparative tests are carried out with the TACA previously mentioned and with tetraacetylthiethylenediamine (TAED).

The washing tests were carried out in a Launder-O-meter with the aid of a perborate washing powder.

The Launder-O-meter is a laboratory washing machine manufactured and sold by Atlas Electric Devices Co. (U.S.A.). The washing conditions are as follows:

temperature	°C.	40
time	minutes	15
water used, hardness	French degrees	16-17
volume	cm. ³	250
perborate washing powder	g./l.	2
Test pieces to be washed (100 cm. ² , about 0.6 g.)		
mixed cotton-polyester fabric soiled with wine		1
mixed cotton-polyester fabric soiled with tea		1

	mean:	19.4	mean:	39.7	mean:	32.4	mean:	39.3	mean:	44.4	

In addition, the results obtained with the four groups of test pieces are summarized in Table 1a.

The washing powder used is the same as that described in Example 1. The test pieces subjected to

washing were soiled as indicated in Example 1; they were, however, subjected to supplementary aging for 4 hours at 70°C.

The results obtained are given in Tables 2 and 2a as follow:

perborate powder was nevertheless replaced by a percarbonate washing powder. This powder was used at the rate of 1.88 g./l. so as to give the washing solution the same oxidizing power as in Example 2. The percarbonate powder had the following composition:

Table 2

Activator, g./l.	Mixed cotton-polyester fabric (65-35) soiled with

	0.3	13.8	19.9	41.9
	0.4	14.9	21.5	45.8

(*)mean of two tests

It is found that the use of small amounts of diacetylated dimethylglyoxime, of the order of 25 percent by weight referred to the sodium perborate, that is, 0.2 mole of activator per gram-atom of active oxygen, makes it possible for the efficiency of the washing solution containing perborate to be practically doubled. Moreover, the additional activity imparted to the powder increases with the amount of activator present.

Table 3a shows the preceding results expressed in terms of relative efficiency.

Table 3a

Activator, g./l. (powder without activator = 100)	Relative efficiency	
	Tea	Wine

0.2	355	167
0.3	418	184
0.4	452	201

EXAMPLE 3

The tests described in this example were carried out under the same conditions as those of Example 2. The

EXAMPLE 4

Tests carried out with the object of determining the action of DMGA on the efficiency of proteolytic enzymes which are sometimes introduced into washing powders.

The washing tests were carried out in a Launder-O-meter under the following conditions:

Temperature duration	°C.	30
water used, hardness	minutes	30
amount	French degrees	17-18
	cm. ³	250
Washing powder:		
perborate (see Example 1 for composition)	g./l.	2
or percarbonate (see Example 3 for composition)	g./l.	1.88
proteolytic enzymes at 300,000 units Delft/g.	g./l.	0.02
Test pieces to be washed (about 100 cm. ²):		
EMPA 112	number	1
EMPA 116	number	1

The DMGA is used at the rate of 0.4 g./l. of washing liquid. ²⁵ DMGA is also very efficient in very hard water.

EXAMPLE 5

The tests of Example 5 were carried out under the same conditions as those indicated in Example 2. The only change relates to the quality of the water. The water used in this example has a very high hardness of 36 French hydrotimetric degrees.

The results of the tests shown in Table 5 indicate that

Table 5

Mixed cotton-polyester fabric (65-35) soiled by tea			
Soil to be eliminated:	69.4		
Soil eliminated, without activator	0.7	i.e. 1.0%	
with DMGA 0.4 g./l.			
(mean of 4 tests)	12.6	i.e. 18.2%	
Relative efficiency, without activator	100		
with DMGA	1820		
Mixed cotton-polyester fabric (65-35) soiled by wine			
Soil to be eliminated:	44.0		
Soil eliminated, without activator	0.6	i.e. 1.4%	
with DMGA 0.4 g./l.			
(means of 4 tests)	15.6	i.e. 35.5%	
Relative efficiency, without activator	100		
with DMGA	2600		

The results obtained are indicated in Table 4. They show that DMGA does not harm the action of enzymes in perborate or percarbonate biological powders.

EXAMPLE 6

Soaking tests were carried out in cold water under the following conditions:

Table 4

etc.) Washing Powder	Cotton				Mean %
	EMPA 112 (blood, India ink)	EMPA 116 (cocoa)	Soil Eliminated	Elim- ination rate in %	
Perborate powder	2.1	2.7	6.9	10.3	6.5
Ditto + enzymes	13.9	17.6	11.6	17.3	17.5
Ditto + enzymes and DMGA	13.9	17.6	12.4	18.5	18.1
Percarbonate powder	2.1	2.7	6.8	10.2	6.5
Ditto + enzymes	11.5	14.6	12.6	18.8	16.7
Ditto + enzymes and DMGA	11.3	14.3	13.7	20.5	17.4

Temperature	°C.	25
Time	hours	½ to 3
Water used, hardness	French degrees	18
quantity	cm. ³	1000
Perborate powder (see Example 1 for composition)	g./l.	5
Test pieces (about 100 cm. ² , 0.6 g.)		
Mixed cotton-polyester fabric soiled by wine	Number 6	
Mixed cotton-polyester fabric soiled by tea	Number 6	

The results are shown in FIG. 1. In this and the following diagram the abscissae represent the soaking time in hours, while the ordinates represent the soil eliminated in percent. Curves I, III, V and VII relate to fabric soiled by tea, while curves II, IV and VI relate to fabric soiled by wine. Curves I and II show soaking tests without activator; curves III and IV were obtained in the presence of 0.1 g. of DMGA per liter; curves V and VI relate to soaking in the presence of 0.5 g. of DMGA per liter, while curves VII and VIII relate to the presence of 1 g. of DMGA per liter.

The curves show the additional efficiency imparted to the soaking powder by DMGA. The amount of soil eliminated by the powder without activator after soaking for 3 hours is already attained after only one-fourth to one-half hour when DMGA is added to the soaking solution.

10 The results obtained are shown in the accompanying diagrams (FIGS. 2 to 5). Diagrams 2 and 3 relate to a concentration of activator of 0.25 g./l. while diagrams 4 and 5 were obtained with an activator concentration of 0.5 g./l.

15 Diagrams 2 and 4 relate to soaking tests with fabrics soiled with tea, diagrams 3 and 5 to fabrics soiled with red wine.

Curves I relate to tests carried out without activator, curves II to tests carried out with DMGA, III with DAG and IV with MEGA.

20 These diagrams clearly show the considerable increase in efficiency of a soaking powder when one of these three activators is introduced into it.

25 Table 6 expresses these results in terms of relative efficiency.

Table 6a indicates the time required for a soaking

Table 6

Nature of Activator	Concentration of Activator g./l.	Relative Efficiency After 3 hours of Soaking:	
		TEA	WINE
nil (I)	0	100	100
DMGA (II)	0.25	176	264
	0.50	239	386
DAG (III)	0.25	176	264
	0.50	231	368
MEGA (IV)	0.25	176	243
	0.50	200	305

EXAMPLE 7

The tests described in this example were carried out under the same conditions as indicated in Example 6.

45 powder containing one of the three diacetylated glyoximes to eliminate an amount of soil equivalent to that removed by the same unactivated powder after soaking for 3 hours.

Table 6a

Nature of Activator	Concentration of Activator g./l.	Soaking time equivalent to a soaking of 3 hours without activator, minutes	
		TEA	WINE
DMGA (II)	0.50	14	13
DAG (III)	0.50	36	14
MEGA (IV)	0.50	42	22

The only change relates to the temperature of the test, which is 22°C.

Two other acetylated glyoximes were tested under the same conditions as DMGA, namely, diacetylated glyoxime (DAG) and diacetylated methylethylglyoxime (MEGA).

60 It can be seen in Table 6a, as we have already shown in Example 6, that after a soaking time of less than ¼ hour with DMGA, the same quantity of soil is eliminated as is removed in 3 hours with the powder containing no activator.

65 In the case of DAG and MEGA this time is slightly longer than one-half hour for fabrics soiled with tea and about one-fourth and one-half hour for fabrics soiled with wine.

What we claim as new and desire to secure by Letters Patent is:

1. A process for the activation, in an aqueous medium, of an active oxygen releasing compound selected from the group consisting of hydrogen peroxide, sodium perborate and sodium percarbonate, which comprises activating said active oxygen releasing compound by an activator selected from the group consisting of diacylated glyoxime and diacylated dialkylglyoxime wherein the alkyl group contains from one to four carbon atoms and the acyl group contains from two to four carbon atoms, said activator being present in a quantity corresponding to about 0.05-1 mole per gram-atom of active oxygen contained in said active oxygen releasing compound.

2. A process according to claim 1 in which the activator is diacetylated methylethylglyoxime.

3. A process according to claim 1 in which the activator is diacetylated glyoxime.

4. A process according to claim 1 in which the activator is diacetylated dimethylglyoxime.

5. A process according to claim 1 in which the peroxide compound is hydrogen peroxide.

6. A process according to claim 1 in which the peroxide compound is sodium perborate.

7. A process according to claim 1 in which the peroxide compound is sodium percarbonate.

8. A solid composition for producing washing and bleaching baths by dissolution in water comprising an active oxygen releasing compound selected from the

10 group consisting of sodium perborate and sodium percarbonate and an activator selected from the group

consisting of diacylated glyoxime, diacylated dialkyl-

glyoxime wherein the alkyl group contains from one to

15 four carbon atoms and the acyl group contains from

two to four carbon atoms, said activator being present

in a quantity corresponding to about 0.05-1 mole per

gram-atom of active oxygen contained in said active

oxygen releasing compound.
